WELL CEMENTING MECHANISM

Clarence E. Burt, Los Angeles, Calif., assignor to
 Baker Oil Tools, Inc., Huntington Park, Calif.,
 a corporation of California

Application May 5, 1939, Serial No. 271,937

22 Claims. (Cl. 166—12)

This invention relates to well cementing mechanism and is more particularly directed to that general character of well cementing apparatus by means of which the so-called tubing method of well cementing is practiced.

It is the principal object of the present invention to provide an improved and efficient well cementing apparatus having particular utility in the "back plugging" of wells and in other plugging operations involving the depositing of cement slurry at a selected zone in a well in sufficient quantity to form therein a relatively long cement plug, the apparatus being capable of being lowered to a position of use by a cementing string of tubing and of being under the operative control of the operator at the derrick floor, such control insuring a proper functioning of the apparatus to pack off the well immediately above the cementing zone, to deposit the cement slurry directly in the lower portion of said cementing zone to displace the well fluid therein, and to gradually elevate the depositing means throughout the cementing operation when such procedure is considered necessary or desirable, there being provisions permitting a retrieving of the cement depositing means and its withdrawal from the well with the cementing string of tubing after completion of the cementing operation.

A practical apparatus of this type will be generally tubular in character and adapted to be run in a well casing at the lower end of a cementing string of tubing by means of which it may be manipulated by an operator at the derrick floor, and it will include in its structure an expansible packer having slips operable to firmly anchor the packer in the surrounding casing, and an expandable packing or sealing element for sealing off the annular space between the packer body and the wall of the casing at the upper end of the cementing zone. The means through which the cement slurry is discharged at or near the bottom of the cementing zone forms the lower end portion of the retrievable cementing string and comprises a tubular mandrel which normally is detachably connected to the packer and has a terminal tail-pipe projecting downwardly therefrom a distance approximating the total height of the cementing zone. In use, the tubing string, carrying the packer and the depending tail-pipe, is run in the well casing to the selected location, the packer is tripped and set by fluid pressure and by manipulation of the tubing string to pack off the casing at the upper end of the cementing zone, a further increase of the fluid pressure will condition the mechanism for a discharge of cement from

the tail-pipe into the lower portion of the cementing zone to displace well fluid therein and completely fill the entire zone with cement. After completion of the cementing operation, the tubing string may be manipulated to disconnect the mandrel from the set packer and will be elevated to withdraw the mandrel and depending tail-pipe through the set packer for removal from the well, the tail-pipe having stripped from its lower end during such withdrawal, a terminal member which will engage and remain in the lower end of the set packer to function as a closure or back-pressure valve preventing upward escape of the discharged cement through the packer. The mechanism is so arranged that, if it becomes desirable or necessary, the tubing string may be disconnected from the set packer and elevated gradually as the cementing operation is in progress, whereby the cement will be discharged at progressively higher elevations as the cement plug is built up thus relieving the pumps of the necessity of lifting or forcing the discharged cement upwardly the length of the long cementing zone.

One form which the invention may assume is exemplified in the following description and illustrated by way of example in the accompanying drawings, in which:

Fig. 1 is a vertical section through a portion of a well bore and casing and showing in section the upper portion of the well cementing apparatus of the present invention in normal condition as it is run in the well casing to position of use.

Fig. 2 is a vertical section through the next adjacent lower portion of said well bore and casing and showing in section the tail-pipe of said cementing apparatus as initially disposed within a screen portion of said casing.

Fig. 3 is a section, similar to Fig. 1, showing the packer in actuated condition, with the tubing string mandrel disconnected therefrom and the entire tubing string assembly being shown in a partly retrieved position as the tail-pipe is being drawn upwardly through the set packer.

Fig. 4 is a section, somewhat similar to Fig. 2, showing the lower portion of the tail-pipe in a partly retrieved position.

Fig. 5 is a vertical section showing the tubing string in an elevated position fully disengaged from the set packer, the terminal closure member of the tail-pipe having been engaged in the packer body and been stripped from the tail-pipe to remain in the set packer to valve said packer against reverse flow of the cement.

Although my improved apparatus may be em-

ployed in various situations where a cement plugging operation is either desirable or necessary, I have in the drawings illustrated its use in a cementing operation involving the plugging of 5 a screen or perforated portion of a combination casing string or liner.

In its preferred form the apparatus comprises two distinct assemblies adapted to be initially connected together and lowered into a well casing 10 or liner to a position of use and to be thereafter disconnected, one thereof constituting a packing means adapted to be left anchored in the casing or liner and being constructed of drillable materials capable of being drilled up in a subsequent 15 drilling operation, and the other thereof constituting the lower portion of a tubular cementing string and including a flow mandrel and a depending cement discharging tail-pipe, and flow controlling mechanism retrievable by withdrawal 20 of the tubing string from the well.

The packing means which I prefer to use is, insofar as its general type is concerned, similar in character to that disclosed in United States Letters Patent No. 2,121,051, issued June 21, 1938, 25 to Thomas M. Ragan and myself.

The packer A in the condition shown in Fig. 1, is run into the well casing B, on a tubular mandrel assembly C, which forms the lower portion of a connecting string of tubing D. This 30 packer has a hollow cylindrical body 10, having a lower abutment shoulder 11, and provided at its upper end with an enlarged abutment collar 12.

An external packing sleeve 13, formed of rubber or other suitable pliable material, surrounds 35 the medial portion of the body 10 and is connected at its lower end to a lower cone 14, which slidably fits said body, while its upper end is connected to an upper cone 15, likewise slidably fitting said body. Normally these cones 14 and 40 15 are connected to the body 10 by shear pins 16 and 17, respectively, the pins 16 of the lower cone having a greater shear value than the pins 17 of the upper cone so that a lesser pressure 45 is required to release the upper cone than that required to release the lower cone.

"Up-pressure" slips 18 are normally connected to the body 10 by shear pins 19 and to the upper cone by shear pins 19a, and "down-pressure" 50 slips 20 are normally connected to the body by shear pins 21 and to the lower cone by shear pins 21a.

It will be noted that a split contractable ring 22, tooth-shape in cross section is disposed within 55 an internal groove in the upper cone 15 in position to engage annular serrations forming on the exterior of the body 10 a series of ratchet teeth 23, said teeth and latch forming a one-way ratchet means which will retain the upper cone 60 latched to the body in operated position.

The body 10, behind the surrounding packing sleeve 13, is provided with lateral ports 24, which communicate with the bore of the body and the lower portion of the body is formed to provide a 65 housing in which is disposed an internal tail-pipe packing sleeve 25 formed of rubber or other suitable pliable packing material.

Referring particularly to Fig. 3, it will be noted 70 that the upper end of the bore of the body 10 is provided with square left-hand female threads 26 adapted to receive similar male threads 26a formed on a sleeve valve member 27 which is incorporated in the tubular mandrel assembly C, and the upper end of the body is formed to 75 provide an annular seat 28 which surrounds the

body bore and will, when the apparatus is in the normal condition shown in Fig. 1, be engaged by an external valve shoulder 29 formed on said valve sleeve 27.

The retrievable assembly C comprises a tubular flow mandrel 30 connected at its upper end to a back-pressure valve housing 31 which in turn is detachably connected to the lower end of the tubing string D, and a depending tail-pipe or discharge nozzle 32 normally extending 10 through the bore of the packer body 10 and the tail-pipe packing sleeve 25 to extend downwardly below the packer to the lower end portion of the cementing zone.

The flow mandrel 30 has a lower portion 30a 15 of reduced diameter which is provided with lateral flow passages 33 and has a collar 34 providing an annular valve seat and valve stop 35. Surrounding and slidably fitting both the upper and lower portions of the flow mandrel, is the 20 valve sleeve 27 which also serves as a sub for detachably connecting the retrievable assembly C to the packer A, and between the upper end of said valve sleeve 27 and a shoulder formed on the upper portion of the mandrel 30 is disposed 25 a compression coil spring 36. For the purpose of transmitting applied torque from the mandrel to the valve sleeve 27, said valve sleeve is keyed to the mandrel 30 by means of diametrically opposed studs 37 projecting laterally in companion 30 vertically disposed elongated slots 38 formed in the upper wall portion of said sleeve, and for the purpose of preventing fluid leakage between the mandrel 30 and the sleeve 27, there is provided 35 a packing ring 39 which is preferably disposed within a groove in the mandrel 30 in position to engage the inner wall surface of said sleeve.

Referring to the upper portion of Fig. 1, it will be observed that the upper valve housing 31 provides a valve chamber in which is disposed a 40 back-pressure ball valve 40 adapted to engage an internal valve seat 41 and close the flow passage of the tubing string at this point to prevent an upward flow of fluid or cement.

This back-pressure valve is of a buoyant character and will for this reason automatically close 45 when the apparatus is lowered into a well containing fluid. However, it is at all times free to open under the influence of a predominating pressure above it, in which event its downward 50 movement will be arrested by a series of upwardly projecting supporting ribs 42 disposed within the valve housing in circularly spaced relationship to provide intermediate passages permitting free downward flow of fluid past the open 55 ball valve.

When the apparatus is conditioned as shown in Fig. 1, the sleeve valve sub 27 will be in its uppermost position on the mandrel 30 to compress the coil spring 36 and uncover the lateral 60 flow passages 33 and will be normally retained in this position by shear pins 43 connecting it to the mandrel 30. The collar 34 of the mandrel portion 30a closely fits within the bore of the packer body 10 as does the lower end of the sleeve 65 valve 27 which, in this run-in condition of the apparatus, is upwardly spaced from the annular valve stop shoulder 35 and thus defines an annular flow chamber 44 communicating with the lateral ports 24 of the packer body 10 and with 70 the lateral flow passages 33 of the mandrel.

The lower end of the depending tail-pipe 32 is normally closed by a terminal closure plug 45 initially secured in the tail-pipe by a shear pin 46. This closure 45 has a cylindrical body 75

portion which is somewhat larger in diameter than the interior diameter of the tail-pipe packing sleeve 25 and is provided with a series of annular serrations forming downwardly facing gripping teeth 47 and below said body portion is an enlarged head formed to provide an angled annular shoulder 48 which subsequently cooperates with an annular valve seat 49 formed in the lower end of the bore of the packer body 10. The lower end of the closure plug 45 is of inverted cone shape and the lower end of the packer body is tapered so as to guide the apparatus as it is lowered into the well casing.

Above the terminal plug 45 the tail-pipe is provided with a series of lateral discharge ports 50 and above said ports a trip ball seat 51 slidably fits in the tail-pipe and is initially attached thereto by a shear pin 52. This seat member forms a part of the flow passage of the retrievable assembly and provides an annular valve seat 53 which will subsequently be engaged by a tripping ball 54 that will be sent down the tubing string by the operator to valve the flow passage above the discharge ports and cause a build up pressure to trip the packer and to thereafter shear the pin 52 and translate said seat member and ball downwardly past the discharge ports until arrested by a stop stud 55 carried by the tail-pipe immediately above its terminal plug.

In practice, the apparatus is conditioned as shown in Figs. 1 and 2 and is lowered into the well casing to a position of use. In the drawings I have illustrated as an example, the use of my improved apparatus in a cementing operation involving the "back plugging" of a perforated or screen portion E of a combination casing or liner in which operation the apparatus has been lowered to position the packer A in the casing closely adjacent the upper end of the screen E with the tail-pipe 32 depending downwardly to the lower portion of the cementing zone which may, due to necessity or to state regulations, extend to a point fifteen or more feet below the packer.

With the apparatus thus positioned in the well casing, circulation may be established for such flushing operations as may be considered desirable or necessary. When the operator at the derrick floor desires to set the apparatus for the cementing operation, he will insert the trip ball 54 into the run in tubing string D and allow it to gravitate down through said string and the mandrel and into the tail-pipe to engage the valve seat 53 of the trip member 51 or he may re-establish the circulation and pump said ball down to its seat in which case the closing of the flow passage by the trip ball will be evidenced to the operator, through the usual circulation pressure gauges, by an abrupt rise in the circulation pressure.

After the trip ball 54 seats to close the fluid passage through the apparatus, fluid pressure will be built up and will be effective through the lateral flow passages 33, the annular flow chamber 44 and the lateral ports 24 to expand and elongate the packer sleeve 13 and shear the pins 17 of the upper cone 15, moving said cone upwardly with sufficient force to shear the pins 19 and 19a of the upper slips 18. With said cone and slips thus freed from the packer body and from each other, said slips will engage the abutment collar 12, and by reason of the co-engaging tapered surfaces of the cone and slips, the slips will be expanded to gripping engagement with the casing wall.

Continued increase of the fluid pressure will shear the pin 52 of the seat member 51 and force said seal member and the trip ball 54 downwardly until arrested by the stop stud 55 (as shown in Fig. 4). This downward translation of the trip ball and its seat member connects the flow passage of the tail-pipe with the lateral discharge ports 50 and effects an immediate drop in the fluid pressure, which pressure drop will inform the operator that the tripping cycle has been completed.

The packer having thus been hydraulically tripped to anchor the upper slips and the casing and maintain the upper end of the packer sleeve stationary, the setting of the packer is completed by subjecting the tubing string to an upward strain sufficient to move the packer body 10, the lower cone 14, the lower slips 20 and the lower end of the packing sleeve relative to the now stationary upper end of the packing sleeve, so as to compress said packing sleeve into sealing condition against the casing wall and packer body until it will compress no further.

The pin 43 of the sleeve valve 21 is sheared and the upward movement of the mandrel will effect a closing of the lateral flow passage 33 and cause the lower end of said valve to be engaged by the stop shoulder 35.

Continued upward movement of the body 10 will shear the pins 16 of the lower cone 14 causing the abutment shoulder 11 to engage the lower slips 20, said movement then shearing the pins 21 and 21a and expanding the lower slips to gripping engagement with the casing wall.

With the packer A thus firmly anchored in the casing against dislodgment in either longitudinal direction, the upward strain on the tubing string is released and the apparatus is then in condition for the cementing operation which will be conducted by pumping cement slurry down the tubing string and its mandrel and tail-pipe to discharge through the lateral discharge ports 50 and into the casing at the lower end of the cementing zone, the discharged cement displacing the well fluid upwardly as said cement flows into the casing and through the screen perforations to completely fill said casing and the well bore throughout the cementing zone. A squeezing pressure may be applied to the discharged cement at any time to insure a complete filling of the cementing zone.

After the cementing operation is completed the cementing string may be withdrawn from the well to retrieve the mandrel assembly from the set packer for future use. This is accomplished by rotating the tubing string a few times to the right to disconnect the left-hand screwthreaded end of the sleeve valve sub 21 from the upper left-hand screw-threaded end of the set packer and then elevating the entire cementing string, the tail-pipe being thus pulled through the tail-pipe packing sleeve 25 until its terminal closure plug 45 is forced into the bore of said packing sleeve to embed its teeth 47 into the packing material and to engage its annular shoulder 48 with the annular valve seat 49 at the lower end of the body of the packer, as shown in Fig. 5, continued upward movement of the tail-pipe shearing the pin 46 to disconnect said terminal plug 45 from the tail-pipe which will be removed from the well, leaving the plug 45 seated in the packer to function as a back pressure valve closing the bore of the set packer against reverse flow of the discharged cement.

During the retrieving of the mandrel assembly

from the set packer, the coil spring 36 will insure a closing of the lateral flow passages 33 by the sleeve valve 27, the lower end of said valve sleeve engaging the annular valve seat and stop 35 to 5 form an additional seat against leakage, as shown in Fig. 3.

It will be pointed out that in the event it is considered necessary or desirable, the mandrel assembly may be disconnected from the set packer at the 10 left-hand screw-threaded connection prior to or at any time during the cementing operation and that the entire cementing string may be gradually elevated as the cementing progresses, this gradual retrieving of the tail-pipe during the discharge of 15 the cement slurry being of particular advantage in enabling the discharge of the cement at progressively higher elevations and thus relieving the pumps of the necessity of lifting or forcing the discharged cement upwardly the entire height 20 of a long cementing zone.

While I have herein disclosed a preferred embodiment of my invention, it is to be understood that various changes may be made in its construction by those skilled in the art without departing from the spirit of the invention as defined 25 in the appended claims.

Having thus described my invention, what I claim and desire to obtain by Letters Patent is:

1. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a fluid discharge tail-pipe depending below said body, said mandrel being adapted for connection to a run in string 40 of tubing and providing an axial flow passage and lateral flow passages communicating with said body ports, means for valving said axial passage below said lateral passages to enable a build up of hydraulic pressure to expand said 45 packing sleeve, said valving means being capable of being subsequently actuated by an additional build up of hydraulic pressure to reopen said axial passage, and means detachably connecting said mandrel to the packer body and releasable to permit the mandrel to be withdrawn from 50 the anchored packer body.

2. In an apparatus of the nature disclosed, a packer body having a longitudinal bore and lateral ports communicating therewith, means 55 operable to anchor said body in a well casing, a packing sleeve surrounding said body and expandable by fluid pressure transmitted through said ports to actuate said anchoring means, a tubular mandrel normally extending through 60 said bore and including a fluid discharge tail-pipe depending below said body, said mandrel being adapted for connection to a run in string of tubing and providing an axial flow passage and lateral flow passages communicating with 65 said body ports, means for valving said axial passage below said lateral passages to enable a build up of hydraulic pressure to expand said packing sleeve, said valving means being capable of being subsequently actuated by an additional 70 build up of hydraulic pressure to reopen said axial passage, and means detachably connecting said mandrel to the packer body and releasable to permit the mandrel to be withdrawn from 75 the anchored packer body, said connecting means including a valve element adapted to

close said lateral flow passages as the mandrel is withdrawn.

3. In an apparatus of the nature disclosed, a packer body having a longitudinal bore and lateral ports communicating therewith, means 5 operable to anchor said body in a well casing, a packing sleeve surrounding said body and expandable by fluid pressure transmitted through said ports to actuate said anchoring means, a tubular mandrel normally extending through 10 said bore and including a fluid discharge tail-pipe depending below said body, said mandrel being adapted for connection to a run in string of tubing and providing an axial flow passage and lateral flow passages communicating with 15 said body ports, means for valving said axial passage below said lateral passages to enable a build up of hydraulic pressure to expand said packing sleeve, said valving means being capable of being subsequently actuated by an additional 20 build up of hydraulic pressure to reopen said axial passage, and means detachably connecting said mandrel to the packer body and releasable to permit the mandrel to be withdrawn from 25 the anchored packer body, and a closure capable 30 of being drawn into the lower end of the body bore and close it against reverse fluid flow, said closure being detachably connected to the lower end of said tail-pipe and adapted to be arrested in its upward movement by said body and thereafter be stripped from the tail-pipe as said tail-pipe is withdrawn through said body bore.

4. In an apparatus of the nature disclosed, a packer body having a longitudinal bore and lateral ports communicating therewith, means 35 operable to anchor said body in a well casing, a packing sleeve surrounding said body and expandable by fluid pressure transmitted through said ports to actuate said anchoring means, a tubular mandrel normally extending through 40 said bore and including a fluid discharge tail-pipe depending below said body, said mandrel being adapted for connection to a run in string of tubing and providing an axial flow passage and lateral flow passages communicating with 45 said body ports, means for valving said axial passage below said lateral passages to enable a build up of hydraulic pressure to expand said packing sleeve, said valving means being capable of being subsequently actuated by an additional 50 build up of hydraulic pressure to reopen said axial passage, and means detachably connecting said mandrel to the packer body and releasable to permit the mandrel to be withdrawn from 55 the anchored packer body, an annular tail-pipe packing sleeve mounted in the lower end portion of the packer body to closely surround said tail-pipe, and a shouldered plug element capable of being drawn into said tail-pipe packing sleeve and close the body bore against reverse fluid 60 flow, said element being detachably connected to the lower end of said tail-pipe and adapted to be arrested in its upward movement by engagement of its shoulder with said body and thereafter be stripped from the tail-pipe as said tail-pipe is withdrawn through said body bore.

5. In an apparatus of the nature disclosed, a packer body having a longitudinal bore and lateral ports communicating therewith, means 70 operable to anchor said body in a well casing, a packing sleeve surrounding said body and expandable by fluid pressure transmitted through said ports to actuate said anchoring means, a tubular mandrel normally extending through 75 said bore and including a fluid discharge tail-pipe

- depending below said body, said mandrel being adapted for connection to a run in string of tubing and providing an axial flow passage and lateral flow passages communicating with 5 said body ports, means for valving said axial passage below said lateral passages to enable a build up of hydraulic pressure to expand said packing sleeve, said valving means being capable of being subsequently actuated by an 10 additional build up of hydraulic pressure to reopen said axial passage, and means detachably connecting said mandrel to the packer body and releasable to be withdrawn from the anchored packer body, an 15 annular tail-pipe packing sleeve mounted in the lower end portion of the packer body to closely surround said tail-pipe, and a shouldered plug element capable of being drawn into said tail-pipe packing sleeve and close the body bore 20 against reverse fluid flow, said element being detachably connected to the lower end of said tail-pipe and adapted to be arrested in its upward movement by engagement of its shoulder with said body and thereafter be stripped from 25 the tail-pipe as said tail-pipe is withdrawn through said body bore, there being retaining means formed on said plug element and adapted to become embedded in the tail-pipe packing sleeve. 30 6. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a fluid discharge tail-pipe depending below said body, said mandrel being adapted for connection to a run in string of tubing and providing an axial flow passage and lateral flow passages communicating with said body ports, means for valving said axial passage below said lateral passages to enable a build up of hydraulic pressure to expand said packing sleeve, said valving means being capable of being subsequently actuated by an additional build up of hydraulic pressure to reopen said axial passage, and means detachably connecting said mandrel to the packer body and releasable to permit the mandrel to be withdrawn from the anchored packer body, said body providing an annular valve seat surrounding the lower end of its bore, an annular tail-pipe packing sleeve mounted in said body immediately above said valve seat to closely surround said tail-pipe, and a plug element having an annular valve shoulder, said element being detachably connected to the lower end of said tail-pipe and adapted to be moved upwardly thereby until arrested by engagement of said valve shoulder with said valve seat and to be thereafter stripped from the tail-pipe as said tail-pipe is withdrawn through said body bore, said plug element being provided with retaining teeth adapted to become embedded in the tail-pipe packing sleeve. 35 8. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a tail-pipe depending below said body, said mandrel being adapted for connection to a run in string of tubing and providing an axial flow passage and lateral flow passages communicating with said body ports and having formed in the lower portion of said tail-pipe lateral discharge ports, means for valving said axial flow passage between said lateral flow passages and said tail-pipe discharge ports to enable a build up of hydraulic pressure to expand said packing sleeve, said valving means being capable of being subsequently actuated by an additional build up of hydraulic pressure to reopen said axial passage, and means detachably connecting said mandrel to the packer body and releasable to permit the mandrel to be withdrawn from the anchored packer body. 40 9. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a tail-pipe depending below said body, said mandrel being adapted for connection to a run in string of tubing and providing an axial flow passage and lateral flow passages communicating with said body ports and having formed in the lower portion of said tail-pipe lateral discharge ports, a tubular valve seat normally retained in said flow passage between said lateral flow passages and said tail-pipe discharge ports by means capable of being disabled and capable, when released, of a limited sliding movement to a position below said discharge ports, a valve element adapted to be sent down the tubing string and mandrel to engage said valve seat and close said axial flow passage to enable a build up of hydraulic pres- 45 50 55 60 65 70 75

- sure to expand said packing sleeve and to subsequently disable said valve seat retaining means and translate said seat and said valve element to a lower position to re-establish communication between said axial flow passage and said tail-pipe discharge ports, and means detachably connecting said mandrel to the packer body and releasable to permit the mandrel to be withdrawn from the anchored packer body.

5 10. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a tail-pipe depending below said body, said mandrel being adapted for connection to a run in string of tubing and providing an axial flow passage and lateral flow passages communicating with said body ports and having formed in the lower portion of said tail-pipe lateral discharge ports, a tubular valve seat normally retained in said flow passage between said lateral flow passages and said tail-pipe discharge ports by means capable of being disabled and capable, when released, of a limited sliding movement to a position below said discharge ports, a valve element adapted to be sent down the tubing string and mandrel to engage said valve seat and close said axial flow passage to enable a build up of hydraulic pressure to expand said packing sleeve and to subsequently disable said valve seat retaining means and translate said seat and said valve element to a lower position to re-establish communication between said axial flow passage and said tail-pipe discharge ports, and means detachably connecting said mandrel to the packer body and releasable to permit the mandrel to be withdrawn from the anchored packer body, and a closure capable of being drawn into the lower end of the body bore and close it against reverse fluid flow, said closure being detachably connected to the lower end of said tail-pipe and adapted to be arrested in its upward movement by said body and thereafter be stripped from the tail-pipe as said tail-pipe is withdrawn through said body bore.

cating with said body ports and having formed in the lower portion of said tail-pipe lateral discharge ports, means for valving said axial flow passage between said lateral flow passages and 5 said tail-pipe discharge ports to enable a build up of hydraulic pressure to expand said packing sleeve, said valving means being capable of being subsequently actuated by an additional build up of hydraulic pressure to reopen said axial passage, and means detachably connecting said mandrel to the packer body and releasable to permit mandrel to be withdrawn from the anchored packer body, said connecting means including a valve element adapted to close said 10 lateral flow passages as the mandrel is withdrawn.

14. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and 25 including a tail-pipe depending below said body, said mandrel being adapted for connection to a run in string of tubing and providing an axial flow passage and lateral flow passages communicating with said body ports and having formed 30 in the lower portion of said tail-pipe lateral discharge ports, a tubular valve seat normally retained in said flow passage between said lateral flow passages and said tail-pipe discharge ports by means capable of being disabled and capable, when released, of a limited sliding movement to a position below said discharge ports, a valve element adapted to be sent down the tubing string and mandrel to engage said valve seat and close said axial flow passage to enable a build up of hydraulic pressure to expand said packing sleeve and to subsequently disable said valve seat retaining means and translate said seat and said valve element to a lower position to re-establish communication between said axial flow passage and said tail-pipe discharge ports, and means detachably connecting said mandrel to the packer body and releasable to permit the mandrel to be withdrawn from the anchored packer body, said connecting means including a valve element adapted to close said lateral flow passages as the mandrel is withdrawn.

15. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a fluid discharge tail-pipe depending below said body, said mandrel being adapted for connection to a run in string of tubing and providing an axial flow passage and lateral flow passages communicating with said body ports, means for valving said axial passage below said lateral passages to enable a build up of hydraulic pressure to expand said packing sleeve, said valving means being capable of being subsequently actuated by an additional build up of hydraulic pressure to reopen said axial passage, and means detachably connecting said mandrel to the packer body and releasable to permit the mandrel to be withdrawn from the anchored packer body, said connecting means including a valve element adapted to close said lateral flow pas-

sages as the mandrel is withdrawn, and tension means tending to translate said valve element to closed position.

16. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a tail-pipe depending below said body, said mandrel being adapted for connection to a run in string of tubing and providing an axial flow passage, and lateral flow passages communicating with said body ports and having formed in the lower portion of said tail-pipe lateral discharge ports, means for valving said axial flow passage between said lateral flow passages and said tail-pipe discharge ports to enable a build up of hydraulic pressure to expand said packing sleeve, said valving means being capable of being subsequently actuated by an additional build up of hydraulic pressure to reopen said axial passage, and means detachably connecting said mandrel to the packer body and releasable to permit the mandrel to be withdrawn from the anchored packer body, said connecting means including a valve element adapted to close said lateral flow passages as the mandrel is withdrawn, and tension means tending to translate said valve element to closed position.

17. In an apparatus of the nature disclosed, a packer body having a longitudinal bore and lateral ports communicating therewith, means operable to anchor said body in a well casing, a packing sleeve surrounding said body and expandable by fluid pressure transmitted through said ports to actuate said anchoring means, a tubular mandrel normally extending through said bore and including a tail-pipe depending below said body, said mandrel being adapted for connection to a run in string of tubing and providing an axial flow passage and lateral flow passages communicating with said body ports and having formed in the lower portion of said tail-pipe lateral discharge ports, a tubular valve seat normally retained in said flow passage between said lateral flow passages and said tail-pipe discharge ports by means capable of being disabled and capable, when released, of a limited sliding movement to a position below said discharge ports, a valve element adapted to be sent down the tubing string and mandrel to engage said valve seat and close said axial flow passage to enable a build up of hydraulic pressure to expand said packing sleeve and to subsequently disable said valve seat retaining means and translate said seat and said valve element to a lower position to re-establish communication between said axial flow passage and said tail-pipe discharge ports, and means detachably connecting said mandrel to the packer body and releasable to permit the mandrel to be withdrawn from the anchored packer body, said connecting means including a valve element adapted to close said lateral flow passages as the mandrel is withdrawn, and tension means tending to translate said valve element to closed position.

18. In apparatus of the character described, a body having a passage and adapted to be lowered in a casing, means carried by said body for engagement with said casing, fluid operated means for moving said means into engagement with said casing, a setting tool within said pas-

sage for conducting fluid under pressure to said fluid operated means; and packing means carried by said body within said passage for sealing contact with said setting tool.

- 5 19. In apparatus of the character described, a body having a passage and adapted to be lowered in a casing, means carried by said body for engagement with said casing, fluid operated means for moving said means into engagement with
- 10 10 said casing, a setting tool within said passage for conducting fluid under pressure to said fluid operated means, and a packing sleeve carried by said body within said passage for slidable sealing contact with said setting tool.
- 15 15 20. In apparatus of the character described, a body having a passage and adapted to be lowered in a casing, slips carried by said body for securing it to said casing, fluid operated means for moving said slips into engagement with said
- 20 20 casing, said body having one or more ports establishing communication between said passage and fluid operated means, a tubular setting tool within said passage having one or more ports establishing communication between the interior
- 25 25 of said tool and said passage, and packing means carried by said body within said passage below said ports for sealing contact with said setting tool.
- 30 21. In apparatus of the character described, a body having a passage and adapted to be lowered in a casing, slips carried by said body for secur-

ing it to said casing, fluid operated means for moving said slips into engagement with said casing, said body having one or more ports establishing communication between said passage and fluid operated means, a tubular setting tool 5 within said passage having a lower terminal opening, said tool being provided with one or more ports establishing communication between the interior of said tool and said passage, a packing sleeve carried by said body within said passage and below said ports for slidable sealing contact with said setting tool, and means for closing the terminal opening in said setting tool.

22. In apparatus of the character described, a body having a passage and adapted to be lowered 15 in a casing, slips carried by said body for securing it to said casing, a cone slidable on said body for moving said slips toward said casing, a pliable packing secured to said cone, said body having one or more ports providing communication be- 20 tween said passage and packing, a tubular setting tool within said passage having a lower terminal opening, said tool being provided with one or more ports establishing communication between the interior of said tool and passage, a 25 packing sleeve carried by said body within said passage and below said ports for slidable sealing contact with said setting tool, and means capable of passing through said tool for closing its terminal opening.

CLARENCE E. BURT.
